UNITED STATES PATENT OFFICE.

HENRY J. RICHARDS, OF WILKES-BARRE, PENNSYLVANIA.

MINER'S LAMP.

SPECIFICATION forming part of Letters Patent No. 335,041, dated January 26, 1886.

Application filed November 23, 1885. Serial No. 183,715. (No model.)

To all whom it may concern:

Be it known that I, HENRY J. RICHARDS, a citizen of the United States, residing at Wilkes-Barre, in the county of Luzerne and State of Pennsylvania, have invented certain new and useful Improvements in Miners' Lamps, of which the following is a specification, reference being had therein to the accompanying drawings.

10 This invention relates to certain improvements in miners' lamps; and it has for its objects to provide for keeping the body of the lamp cool, so that it cannot take fire and melt or become otherwise injured from fire; to protect the wick and the flame from dripping water when sinking shafts and the like, and to provide a lamp which may be cheaply constructed, and can be used either as a miner's lamp or an ordinary lamp, as occasion may 15 require. These objects I attain by the means illustrated in the accompanying drawings, in which—

Figure 1 represents a side elevation of my improved lamp complete; Fig. 2, a vertical 25 sectional view of the same; Fig. 3, a detached perspective view of the hood which protects the lamp from dripping water, and Fig. 4 a horizontal sectional view of the lamp.

The letter A indicates the body of the lamp, 30 which is constructed of metal or any other suitable material. From the shoulders of the body the neck of the lamp extends vertically upward, as indicated by the letter B, to form a seat for the stopper or cork C, which is provided with an eyebolt, D, to which one end of a chain, E, is attached, the other end being secured to the hook F of the lamp.

To the neck of the lamp is secured the upper end of a jacket or skirt, G, which surrounds 40 the body, leaving an annular space, H, between it and said body, as shown. The upper part of said jacket or skirt is provided with a series of apertures or openings, I, so that the air may circulate freely around the lamp, and thus keep it from heating.

K indicates the wick-tube, which extends obliquely from the side of the lamp near its lower end, passing through a suitable opening in the jacket or skirt.

Through the upper part of the skirt, and 50 entirely through the lamp, are extended the tubes L L'. The said tubes are open at both ends, and are securely fastened to the lamp-body and to the jacket or skirt, strengthening the parts and producing a substantial lamp. 55 Into the tube L' is inserted a wire picker or instrument, M, to be used for regulating and adjusting the wick when required. The other tubes, L L, form supports for the wires N of the hood or shield P, which extends forward over 60 the end of the wick-tube when in place, thus protecting the wick and the flame from dripping water. The lamp at one side is provided with the usual hook, as above mentioned, by which it can be secured to the hat of the miner. 65

By removing the cork and substituting an ordinary lamp-burner, the lamp may be used as an ordinary lamp, and various burners may be thus substituted to increase the utility of the lamp, if desired. 70

Having thus described my invention, what I claim, and desire to secure by Letters Patent, is—

1. The combination, with the lamp-body and the skirt or jacket, of the tubes extending 75 through the body and secured to the same and to the jacket, substantially as and for the purposes specified.

2. The combination, in a miner's lamp, of the tubes extending vertically through the 80 same and the hood having supporting wires adapted to fit in two of the tubes to hold the hood over the flame, substantially as specified.

3. The combination, in a miner's lamp, of the lamp-body and surrounding jacket, the 85 vertical tubes extending through the body and jacket, the shield having wires adapted to fit in two of said tubes, and the picker fitted in the remaining tube, substantially as and for the purposes specified. 90

In testimony whereof I affix my signature in presence of two witnesses.

his
HENRY J. + RICHARDS.
mark.
